L. J. BRUNE.

WINDOW SASH OPERATING MECHANISM.

APPLICATION FILED NOV. 11, 1916.

1,251,336.

Patented Dec. 25, 1917.

UNITED STATES PATENT OFFICE.

LOUIS J. BRUNE, OF ALGIERS, LOUISIANA.

WINDOW-SASH-OPERATING MECHANISM.

1,251,336.

Specification of Letters Patent. Patented Dec. 25, 1917.

Application filed November 11, 1916. Serial No. 130,894.

To all whom it may concern:

Be it known that I, LOUIS J. BRUNE, a citizen of the United States, residing at Algiers, in the parish of Orleans and State 5 of Louisiana, have invented certain new and useful Improvements in Window-Sash-Operating Mechanisms; and I do hereby declare the following to be a full, clear, and exact description of the invention, such as 10 will enable others skilled in the art to which it appertains to make and use the same.

This invention relates to operating mechanism for the upper and lower sashes of a window, and an object of the invention is 15 the provision of a novel form of mechanism of this character that will admit of the simultaneous movement of both sashes either to open or closed position.

Another object of the invention is the 20 provision of operating mechanism for admitting of the above object being carried out, and which has associated therewith a novel form of locking mechanism that can be moved to releasing position only from 25 the inner side of the window.

Other objects will appear and be better understood from that embodiment of my 30 invention of which the following is a specification, reference being had to the accompanying drawing forming a part thereof, in which:

Figure 1 is an inner side view of a window, having one side thereof in section, so as to show the operating mechanism,

Fig. 2 is a section taken on the line 2—2 of Fig. 1,

Fig. 3 is a section taken on the line 3—3 of Fig. 1,

Fig. 4 is a section taken on the line 4—4 of Fig. 2,

Fig. 5 is a section taken on the line 5—5 of Fig. 2.

Referring to the drawing in detail, the letter A designates a window frame having 45 mounted therein a lower sash B and an upper sash C.

Mounted in one side of the window frame A is a pair of spaced vertical shafts 1 and 2, the said shafts 1 and 2 being of a length 50 co-equal with the height of the window frame and have their upper and lower ends journaled, respectively, in bearings 3 and 4 located in the upper and lower sides of the window frame, as shown more particularly 55 in Fig. 2 of the drawing. The shaft 1 passes through a vertical recess 5 formed in

the adjacent side of the lower sash B, and the shaft 2 extends through a similar recess formed in the adjacent side of the upper sash C. The shaft 1 is provided with a 60 spiral groove 6, which passes around the shaft and extends throughout the length of the shaft, and the shaft 2 is similarly provided with a groove 7, which extends throughout the length of the shaft 2, and 65 around the shaft 2 in the same direction in which the groove 6 extends around the shaft 1, as shown in Fig. 2 of the drawing. Located within the recess 5 in the lower sash B is an elongated plate 8, which extends 70 throughout the length of the groove 5 and engages the inner wall of the groove and has its upper and lower terminals bent and extended at right angles to provide attaching flanges, which are secured, respectively, 75 to the upper and lower sides of the window sash B. The plate 8 is provided with a plurality of laterally extending spaced tingers 9, which engage in the spiral groove 6 in the shaft 1. When movement is imparted to the lower sash B the fingers 9 will travel in the spiral groove 6 in the shaft 1 and effect rotation of the latter. The upper end of the shaft 1 is provided with a gear wheel 10, which meshes with a similar 80 gear 11 mounted on the upper end of the shaft 2. When the shaft 1 is rotated the intermeshing gears 10 and 11 will be rotated and rotation will be imparted to the shaft 2. A plate 12 is mounted within 85 the recess formed in the upper sash C and extends throughout the length of the recess in the upper sash, and has its opposite terminals bent and extended at right angles 90 to provide attaching flanges which are secured, respectively, to the upper and lower sides of the upper sash C. The plate 12, like the plate 8, is provided with a plurality of laterally extending and spaced fingers, 95 the said fingers on the plate 12 being designated by the numeral 13 and are received by the spiral groove 7 formed in the shaft 2. When the lower sash B is raised upwardly, rotation will be imparted to the shaft 1, and by virtue of the gears 10 and 11, the 100 shaft 2 will receive rotation in a direction opposite to the direction of rotation of the shaft 1, and by reason of the fact that the groove 7 in the shaft 2 extends around the shaft 2 in the same direction in which the 105 groove 6 extends around the shaft 1, the groove 6 extends around the shaft 1, the fingers 13 on the plate 12 will travel down- 110

wardly in the groove 7 and effect lowering of the upper sash C. Likewise, a downward movement of the lower sash B will cause the shaft 1 to rotate in the opposite direction, 5 which in turn will, through the medium of the gears 10 and 11 rotate the shaft 2 in that direction in which the fingers 13 on the plate 12 will be caused to travel upwardly in the groove 7 and effect raising 10 of the upper sash C.

A ratchet 14 is mounted on the lower end of the shaft 1 and is keyed thereto for rotation with the shaft 1, and the said ratchet rotates in a recess 16 formed in the lower 15 side of the window frame, the said recess communicating with an elongated recess 17, which opens into the inner surface of the lower side of the window frame. A lever 18 is pivoted within the recess 17 and has 20 one end pointed and extended into the recess 16 and adapted to interchangeably engage the teeth of the ratchet 14. The inner end of the lever is normally held in engagement with the ratchet through the employment of 25 a spring 19 which is mounted on one wall of the recess 17 and bears against the outer end of the lever 18. The terminal of the outer end of the lever 18 extends beyond the inner surface of the lower side of the window 30 frame and serves as a manipulating portion to admit of the convenient operation of the lever 18 when it is desired to withdraw the lever from engagement with the ratchet 14. By virtue of the provision of 35 the ratchet 14 and lever 18, the window sashes B and C can be held at any point desired, within the window frame; also when the window sashes B and C are moved to closed position and the lever 18 engages the 40 ratchet, it will be impossible for the window sashes B and C to be moved to open position from a point exterior of the building.

It is evident that various changes might be resorted to in the construction, form and arrangement of the several parts without departing from the spirit and scope of the invention as claimed.

What I claim is:

1. The combination with the movable upper and lower sashes of a window, of shafts 50 located adjacent the respective sashes and operatively connected for rotation in opposite directions and having spiral grooves thereon, and means associated with each sash 55 for engaging in the groove in the adjacent shaft, whereby upon movement of either sash in one direction by force applied directly to that sash movement will be imparted to the other sash in the opposite direction.

2. The combination with the movable sashes of a window and shafts located adjacent the respective sashes and operatively connected for rotation in the opposite directions and having spiral grooves thereon, of 65 plates mounted on the sashes, and fingers carried by the plates and engaging in the grooves in the shafts so that when either shaft is moved in one direction by force applied directly to that sash, movement will 70 be imparted to the other sash in the opposite direction.

3. The combination with the movable sashes of a window, of shafts located adjacent the respective sashes and operatively 75 connected for rotation in opposite directions, means associated with each sash and operatively engaging the adjacent shaft so that upon movement of either sash in one direction by force applied directly to that sash movement will be imparted to the other sash in the opposite direction, a ratchet carried by one of the shafts, and means for interchangeably engaging the teeth of the ratchet so as to normally hold the last-mentioned shaft against rotation, for the purpose specified.

4. The combination with the movable upper and lower sashes of a window, of a pair of shafts located at one side of the window 80 casing, and operatively connected for rotation in opposite directions and having spiral grooves therein, and means associated with each sash for engaging in the groove in the adjacent shaft, whereby the movement of 85 one sash by force applied directly to that sash will impart movement to the other sash in the opposite direction.

5. The combination with a window casing, of upper and lower sashes movably mounted 100 therein and each having a vertical recess located in one side thereof and extending throughout the entire length thereof, a pair of spirally grooved shafts journaled within the casing at one side thereof and extending through the recesses in the sashes, plates equal in length to the length of the sashes and located within the recesses and secured to the sashes, a row of relatively spaced fingers extending throughout the entire length 110 of each plate and engaging in the groove of their respective shafts, and a pair of intermeshing gears fixed to the upper ends of the shafts.

In testimony whereof I affix my signature 115 in presence of two witnesses.

LOUIS J. BRUNE.
